[57] CLAIM

The ornamental design for a pavement sealant spreader or the like, substantially as shown and described.

DESCRIPTION

FIG. 1 is a top plan view of a pavement sealant spreader showing in my new design;

FIG. 2 is a side elevational view taken from the left side of FIG. 1;

FIG. 3 is a front elevational view thereof;

FIG. 4 is a rear elevational view thereof;

FIG. 5 is a side elevational view taken from the right of FIG. 1;

FIG. 6 is a bottom plan view thereof.

Fig. 1.

Fig. 2.
